UNITED STATES PATENT OFFICE.

WALThER HIBY, OF NOORDWIJK AAN ZEE, NETHERLANDS, ASSIGNoR TO JOHAN CHRISTIAAN BARON VAN HAERSOLTE VAN HAERST, OF DRIEBERGEN, NETHERLANDS.

SUBHEATED COKE OVEN WITH VERTICAL HEATING FLUES.

Application filed July 13, 1920. Serial No. 396,006.

To all whom it may concern:

Be it known that I, WALThER HIBY, a subject of the German Republic, residing at Noordwijk aan Zee, the Netherlands, have invented certain new and useful Improvements in Subheated Coke Ovens with Vertical Heating Flues (for which I have applied for a patent in Germany January 3, 1916), of which the following is a specification.

The easy accessibility and the very convenient manner of regulation of the gas-burners of the so-called subheated ovens from the passages underneath the ovens has been the main reason for the wide adoption of this kind of an oven, but up to now the exact regulation of the air, necessary for each burner, was not possible or very difficult and incomplete. By the present invention this fault has been avoided in the following manner:

Between the floors of the ovens and the ceiling of the subways an individual-air-chamber for each single burner has been arranged, the openings of which for the admission of the air can also be regulated from the passage ways underneath the ovens; the outlets of each individual gas-burner and of the corresponding air chamber connect at the lower end of the corresponding vertical heating flue. The invention is represented on the drawing in connection with a coke oven with a double row of heating flues, and two heating flues with two burners and two checker-work-chambers are connected at the upper end of the heating flues and form a closed heating-system. The construction is shown in Figures 1, 2, 3, 4 and 5.

Between the oven-chambers *a* are the vertical heating flues *b* and *b*₁ adjoining one another and each pair of flues being connected at the upper end and form a closed heating system. To each flue *b* corresponds a tuyere burner passage *c* and to each flue *b*₁ a tuyere or burner passage *c*₁ the tuyere or burner passages being accessible from below. To each tuyere or burner passage *c* and *c*₁ corresponds again a closed chamber *d* and *d*₁, filled with brick-checker-work; these chambers are arranged underneath the adjoining oven floors and the working of the oven is carried out in such a manner, that

the direction of the draught is the same in the two adjoining chambers underneath each oven. The ovens, including the oven chambers and preheating devices, are raised so as to provide subways beneath them from which to regulate the valves. In the form of the invention illustrated the ovens are carried on posts *p*. The heating flues between two adjacent oven chambers and the checkerwork regenerators for preheating the air supplied to the flues and for receiving the waste heat therefrom are arranged in pairs. A division wall *b*² separates the flues. A wall *d*² separates the regenerators. Each pair of flues and regenerators forms a heating unit, supplied with a regulatable amount of air and gas, the valves for regulating being manipulated from the subways beneath the oven structure. The adjoining regenerators which lie beneath each oven chamber are also separated from each other by a wall *d*³. A series of units or pairs of flues and regenerators is thus provided running lengthwise of the oven chamber, each heating unit or pair being separated from the adjacent unit. The walls *b*³ separate the flues and the walls *g*³ and *g*³ the brickwork separate the regenerators. The regenerators and flues of each unit are completely enclosed. These units form a series of separate, independent, self-contained heating systems arranged in rows along each oven chamber. By alternately starting and reversing the draught, the flow of heating gases through each unit will be reversed.

All the checker-work-chambers *d* of one row connect with an underlying flue *e* through openings *f*, and all the chambers *d*₁ of another row with a flue *e*₁ through openings *f*₁. The area of the openings *f* and *f*₁ can be regulated from below by specially shaped valve heads *g* and *g*₁ respectively. The air enters the flues *e* and *e*₁ by openings *h* and *h*₁, which are closed by flap-valves; the latter are opened and closed with the changing of the draught direction in the oven.

The waste-gases from the heating flues *b* and *b*₁ pass through the respective checker-work-chambers *d* and *d*₁, through the sole-flues *e* and *e*₁, the pipe connections *i* and *i*₁ to the chimney-flue *l* and from there into

the open air. In the pipe connections i and i_1 are flap-valves k and k_1 , which are also periodically opened and closed.

The draught in the flues and chambers is 5 reversed from time to time and the working is carried on in the following manner: In one case the heating gases pass through tuyere or burner passage c and the air for combustion through the openings h , the 10 sole-flues e , the checker-work-chambers d to the heating-flues b ; in these heating-flues the combustion takes place in a vertical direction. The waste-gases travel downwards 15 through heating-flues b_1 , checker-work-chambers d_1 , sole-flues e_1 , pipe connections i , and pass the opened flap-valves k_1 to the chimney flue l and to the chimney; the flap-valves h_1 and k are closed.

About every half hour, the draught-direction 20 is reversed and now the heating-gases enter through tuyere or burner passage c_1 , the air through opening h_1 , sole flues e_1 , checker-work-chambers d_1 , to the heating-flues b_1 ; the waste-gases travel 25 downwards through flues b , chambers d , sole-flues e , pipe connections i , pass the opened flap-valves k and go through the chimney-flue l to the chimney, while the flap-valves h and k_1 are closed.

30 The importance of the invention consists chiefly in the arrangement that for each individual heating-flue gas and air can be regulated in a remarkable simple manner from the substructure underneath the oven 35 and that consequently a uniform heating of the whole length of the oven wall is ensured with absolute certainty. Both gas and air are regulated in a practically cold state, so that all the regulating arrangements may 40 be easily handled and kept in good order.

Having now described my invention, what I claim as new is:

1. In a horizontal coke oven with vertical heating flues, said oven being raised 45 and provided with subways underneath the oven to permit the operation of the regulating devices, the combination of a plurality of tuyeres for the introduction of the heating gas arranged in rows beneath the 50 heating flues, and a row of separated regenerator chambers for the preheating of the air, means for supplying air to said row of regenerator chambers, one air regenerator chamber by the side of each tuyere, both 55 the tuyeres and the air regenerator chambers being situated in the space between the floors of the ovens and the ceilings of the subways.

2. In a horizontal coke oven with vertical heating flues, said oven being raised 60 and provided with subways underneath the oven to permit access to and operation of the regulating devices, the combination with said vertical flues, of a plurality of tuyeres 65 for the introduction of the heating gas, ar-

ranged in rows underneath the heating flues, a row of separated, checkerwork regenerators for preheating the air, one air regenerator by the side of each tuyere, a flue underneath each row of checkerwork air regenerators, means for supplying air to said row of regenerators comprising connections between said flue and each regenerator, a valve controlling each of said flues, the tuyeres and the air regenerators being situated in the space between the floors of the oven and the ceilings of the subways.

3. In a horizontal coke oven with vertical heating flues, said oven being raised 70 and provided with subways underneath the oven to permit access to and operation of the regulating devices, the combination with said vertical flues of a row of tuyeres for supplying the gas arranged beneath the heating flues, a row of separated, checkerwork regenerators for preheating the air, one regenerator by the side of each tuyere and means for separately regulating the amount 80 of air passing through each regenerator, said air regulating means being regulatable and accessible from the subways and said tuyeres and said checkerwork regenerators being situated in the space between the floors of the oven chambers and the ceilings of the 85 subways.

4. In a horizontal coke oven with vertical heating flues, said oven being raised 90 and provided with subways underneath the oven to permit access to and operation of the regulating devices, the combination with 95 said vertical flues of oven chambers, heating flues between the oven chambers, each pair of flues being connected at the upper end, two rows of checkerwork regenerators for preheating the air supplied to said flues, 100 two rows of tuyeres for supplying gas to said flues, said tuyeres being arranged alongside of said regenerators, there being one tuyere for each regenerator, thus providing a series of pairs of flues and regenerators 110 running in rows along the oven chamber and means for alternately reversing the draught in the flues and regenerators.

5. In a horizontal coke oven with vertical heating flues, said oven being raised and 115 provided with subways underneath the oven to permit access to and operation of the regulating devices, the combination with said vertical flues, the flues being arranged in pairs and each pair of flues being connected at the upper end, said pairs of flues being separated from each other, of oven chambers heated thereby, two rows of separated, checkerwork regenerators for preheating the air supplied to said flues, two 120 rows of tuyeres for supplying gas to said flues, said tuyeres and said regenerators being arranged in the space between the floors of the oven chambers and the ceilings of the 125 subways, a plurality of air and waste 130

gas flues running lengthwise of the oven chamber and likewise located between said oven chamber floors and said ceilings, connections between said flues and said regenerators and a plurality of valves, independently operable for controlling the connections between the flues and the regenerators, said valves being accessible and regulatable from the subways, and means for reversing the draught in the flues and regenerators.

6. In a horizontal coke oven with vertical heating flues, said oven being raised and provided with subways underneath the oven to permit the operation of the regulating devices, the combination with said vertical flues, of a plurality of tuyeres for the introduction of the heating gas, arranged in rows underneath the heating flues, the flues between the oven chambers being separated by a division wall for part of their length and connected at the top, so as to form a pair of flues for each unit, a row of separated, checkerwork regenerators, one regenerator by the side of each tuyere, said oven being provided with subways underneath the oven to permit the operation of the regulating devices, the combination with said vertical flues, of a plurality of tuyeres for the introduction of the heating gas, arranged in rows underneath the heating flues, the flues between the oven chambers being separated by a division wall for part of their length and connected at the top, so as to form a pair of flues for each unit, a row of separated, checkerwork regenerators, one regenerator by the side of each tuyere, said oven being provided with one regenerator for each flue of the pair of flues, and with one tuyere for each of said flues and there being two rows of checkerwork regenerators below each oven chamber which are separated by a division wall between the bottoms of the oven chambers and the ceilings of the subway, and means for alternately reversing the draught in the flues and regenerators.

7. In a horizontal coke oven with vertical heating flues, said oven being raised and provided with subways underneath the oven to permit the operation of the regulating devices, the combination with said vertical flues, of a plurality of tuyeres for the

introduction of the heating gas, arranged in rows underneath the heating flues, the flues between the oven chambers being separated by a division wall for part of their length and connected at the top, so as to form a pair of flues for each unit, a row of separated, checkerwork regenerators, one regenerator by the side of each tuyere, said oven being provided with one regenerator for each flue of the pair of flues, and with one tuyere for each of said flues and there being two rows of checkerwork regenerators below each oven chamber which are separated by a division wall between the bottoms of the oven chambers and the ceilings of the subway, and means for alternately reversing the draught in the flues and regenerators.

8. In a horizontal coke oven with vertical heating flues, said oven being raised and provided with subways underneath the oven to permit access to and operation of the regulating devices, the combination with said vertical flues of a row of tuyeres for supplying the gas arranged beneath the heating flues, a row of separated, checkerwork regenerators for preheating the air, one regenerator by the side of each tuyere and a plurality of valves, one for each air regenerator, each valve having a stem accessible from the subway, said valves separately regulating the amount of air passing thru each regenerator.

In testimony whereof I affix my signature.

WALTHER HIBY.
